ATTORNEY.

UNITED STATES PATENT OFFICE.

KARL E. PEILER, OF WEST HARTFORD, CONNECTICUT, ASSIGNOR TO HARTFORD-FAIRMONT COMPANY, OF HARTFORD, CONNECTICUT, A CORPORATION OF NEW YORK.

FEEDING MOLTEN GLASS.

Application filed November 25, 1925. Serial No. 71,369.

To all whom it may concern:

Be it known that I, KARL E. PEILER, a citizen of the United States, residing at West Hartford, in the county of Hartford 5 and State of Connecticut, have invented certain new and useful Improvements in Feeding Molten Glass, of which the following is a specification.

This invention relates to improvements in 10 the art of feeding molten glass from a melting tank, a pot, or other container or source of supply, and delivering it in mold charges of uniform and controllable size and shape to apparatus for pressing, blowing or otherwise 15 fabricating the charges into glassware.

This application is a continuation of several prior applications, as pointed out below, and is filed for the purpose of claiming an important advance in the glass feeding 20 art which has been given the name of "phase-changing". This expression, as used herein, should be understood as meaning change in the relative time of occurrence of the operations controlling the formation of 25 the mold charges, ready for severing, and the operation of severing these mold charges, as these operations are repeated in successive 30 cycles. Variation in this relative time accomplishes valuable results in respect to controlling the shape and weight of the delivered charges. It has been developed by 35 me through a series of mechanisms which constitute a series of progressive improvements, and several of these mechanisms are shown herein for the purpose of indicating the manner in which this invention has been developed.

The invention, to be protected hereby, 40 contemplates in one of its broader aspects the method in which glass in a viscous condition is intermittently allow to sag down from an overhead support past a severing plane to form a mold charge in suspension below the severing plane. The charge is 45 severed from the glass remaining above the severing plane and is then received in a mold. The shape, particularly the length, of the severed charge is influenced and controlled by properly coordinating the time 50 of severance in relation to the essential steps which produce the suspended mass from which the charge is to be severed.

Variations in this relative time between the severing operation on the one hand and

other operations influencing the formation 55 of the charge on the other hand, herein termed "phase-changing", produce changes in the shape of the charges.

In certain forms of this invention shown herein, a variation in the time at which the 60 glass for the mold charge issues from a furnace is made in respect to the time of severance. In such embodiments of this invention, the variation in phase between feeding 65 and severing may accomplish not only a regulation of the lengths of the severed charges, but also a regulation of the weight of the charges.

The later developed forms of the invention 70 herein claimed contemplate, in combination with the phase change before referred to, lifting the stud of glass left after each severing operation at a variable time in respect to the time of severing, in order to shape the lower end of the stub of glass left 75 above the severing plane and to thus shape the lower end of the next succeeding charge. Phase-changing between lifting the glass and severing the glass is specifically claimed elsewhere by me, and is therefore not 80 claimed per se herein.

Not only does my invention involve the methods above stated, but also apparatus for carrying out those methods.

The several prior applications in which 85 this invention is disclosed in various aspects, and of which this application is a continuation in part, include an application Serial No. 713,143, filed August 3, 1912, an application Serial No. 157,943, filed 90 March 28, 1917 (it in itself being a continuation of application Serial No. 856,548, filed August 13, 1914), an application Serial No. 294,792 and an application Serial No. 294, 95 793, both filed May 5, 1919.

It is a prominent characteristic of molten glass that when it issues or is withdrawn from the furnace or other container, and is exposed to the colder surroundings outside of the furnace, it acquires a partially chilled 100 surface or skin, known in this art as "enamel". This enamel is coldest and stiffest on its outer surface, and gradually merges into the hot and more plastic interior of the glass. When a charge of this glass is delivered to a mold, any undue stretching, rupture, or infolding of the enamel will cause 105 defects in the article being made. Any trap-

ping of air by the glass, due to lapping or folding of the surface of the glass as it is delivered to the molds, will also cause defects. To avoid these defects it is desirable to pre-
 5 form the mold charge, before it enters the mold, so that its external contour will closely approximate the interior contour of the mold walls, or at least that portion of the mold which receives the charge.
 10 This is of special importance in the making of blown glassware. A mold charge, which is to form a narrow-necked bottle, for example, should be pre-formed as an elongated cylinder, so that its entire surface
 15 may as nearly as possible contact equally with the mold walls for the same length of time. Unequal contact of different portions of the surface, or unequal duration of contact of the different portions, tends to pro-
 20 duce an unsymmetrically chilled and enameled blank or parison, which will not blow out uniformly, because the hotter portions will stretch more than the cooler portions, resulting in a poor bottle having a wall
 25 of uneven thickness.

These conditions have evidently been recognized to some extent by the hand gatherer, practicing his ancient art, who, by manipulation of his punty or gathering rod
 30 during the gathering operation, performed his gather or mold charge, as well as he could by this primitive method, to fit the mold, or that portion of the mold that receives the gather, thus attempting to avoid
 35 undue deformation of the mold charge when deposited in the mold. On the other hand, these conditions have received little or no attention in the gathering or feeding of molten glass as heretofore practiced by ma-
 40 chine or other automatic methods prior to my invention of the apparatus herein disclosed. The present application is concerned with the accomplishment of this shaping by the aid of the phase-changing operations
 45 outlined above.

In the accompanying drawings:

Figure 1 is a general front elevation of an apparatus invented by me and adapted to carry out the method hereinafter claimed,
 50 certain of the lower parts and the base of the apparatus being omitted;

Figure 2 is a front elevation, partly in section along the line 2—2 of Fig. 3, of the center portion of the machine shown in Figure 1, and showing the impellers, outlet and shear carriers, with the right hand shear in place and the left hand shear omitted.

Figure 3 is a side elevation, partly in section along the center line of Fig. 2, with the shear mechanism omitted, and showing the mounting of the primary and secondary impellers as well as the driving connection and adjustment for stroke and position of the secondary impellers.

Figure 4 is a side elevation, partly in sec-

tion along the center line of the machine shown in Fig. 1, and showing the machine equipped with a single impeller only, the secondary impeller not being used.

Figures 5 and 6 are enlarged views of the 70 single impeller of Fig. 4, coacting with the temporary holder or container and illustrating their action.

Figure 7 is a plan view of the mechanism for driving the impellers shown in Fig. 1. 75

Fig. 8 is a sectional elevation taken along the line 8—8 of Fig. 7, showing the cam shaft and cams for driving the impellers and their adjustment, as well as the mounting of the primary impeller. 80

Figure 9 is a section in elevation along the line 9—9 of Fig. 7, showing the driving mechanism of the primary impeller with the parts adjusted to give this impeller its shortest stroke. 85

Figures 10 and 11 are left hand elevations of the cam governing the motion of the secondary impeller shown in Fig. 1, and showing removable portions of the cam surface in different positions. 90

Figure 12 is a side elevation of a machine embodying another form of my invention, shown partly in section, with the shear mechanism omitted, but showing the glass furnace and its conduit for the molten glass. 95

Figure 12^a is a front elevational view of the upper portion of the structure shown in Fig. 12.

Figure 13 is a front elevation, partly in section on the line 13—13 of Fig. 14, of the center portion of the machine shown in Fig. 12, and shows the impeller, outlet and shear carriers, with the right hand shear in place and the left hand shear omitted. 100

Figure 14 is a side elevation taken in section along the center line of Fig. 13 with the shear mechanism omitted and showing the impeller drive connection and adjustments for stroke and position. 105

Fig. 15 shows an elevation of the impeller driving cam embodied in the machine of Fig. 12, with its driving gears. 110

Fig. 16 is a sectional elevation on line 16—16 of Fig. 15.

Fig. 17 is a sectional elevation on line 115 17—17 of Fig. 15.

Fig. 18 is a bottom view of a section on line 18—18 of Fig. 15.

Fig. 19 shows a side elevation of the worm adjustment for the impeller cam used in the machine of Fig. 12. 120

Fig. 20 is a front elevation showing in reduced scale the general features of another embodiment of my invention.

Fig. 21 is a plan view in section taken 125 along the line 21—21 of Fig. 20.

Fig. 22 is an end elevation, partly in section, of the machine shown in Fig. 20.

Fig. 23 is an opposite end elevation, partly in section of the same machine. 130

Fig. 24 is a plan view of the upper mechanism of the machine shown in Fig. 20.

Fig. 25 is a front elevation, partly in section taken on the line 25—25 of Fig. 24.

Fig. 26 is a front elevation, partly in section, of a portion of the shear mechanism shown in Fig. 20.

Figs. 27 and 28 are side elevations illustrating formed variations of the glass gatherers obtainable by adjusting the feeding movements of the paddle shown in Fig. 20.

Fig. 29 is a front view of another form of apparatus embodying the broader aspects of my invention, in section taken on the line 29—29 of Figs. 30 and 31.

Fig. 30 is a side view projected from Fig. 29 and in section taken on the line 30—30 of Fig. 31.

Fig. 31 is a plan view in section taken on the line 31—31 of Fig. 29.

Figs. 32 to 35 inclusive are detailed views in larger scale, showing the gathering head of Fig. 29 at successive stages in its operation.

Figs. 36 and 37 are detailed views showing part of the drive for the punty embodied in Fig. 29.

Figs. 38 to 42 are diagrammatic sections illustrating, for convenient reference, the several embodiments of the invention which are shown in more detail in the preceding figures. Fig. 38 is a simplified representation of the punty device, as shown in Fig. 29. Fig. 39 shows the paddle feeder and is similar to Fig. 27, with the addition of the paddle of Figs. 20 and 21 as this paddle is shown in Fig. 20 of the original application Serial No. 157,943. Fig. 40 is similar to Fig. 4 and shows the paddle feeder with the bowl spout. Fig. 41 is similar to Fig. 3 and shows the paddle or primary impeller associated with the secondary impeller, plunger or needle, this feeder being frequently termed the "paddle-needle" feeder. Fig. 42 is similar to Fig. 12 and shows a feeder having a vertical impeller without the paddle of Fig. 41.

The device shown in Figs. 1 to 11 (as to which this application is a divisional continuation of the aforesaid application Serial No. 294,793), represents a glass feeding machine which is in extensive commercial use. It comprises a channel or conduit 1, Fig. 3, connected to a glass furnace and provided at its outer end with a holder or container 2 for the glass having an outlet 3 for discharge of the glass. This container 2 is partly separated from the channel or conduit by the wall or dam 6 so that the glass will not flow into it unless acted upon by the paddle or impeller 4. The wall or dam 6 may be omitted and the holder or container 2 may be at a lower level, or the glass may be at a higher level so that the glass 65 will flow into the container from the chan-

nel, but in order to secure better control of the discharge of the glass, the arrangement shown is preferred. If desired, the depth of glass in the channel may be regulated by a vertically adjustable gate, such, for example, as that shown in Patent No. 1,349,551, granted on the application of K. E. Peiler on August 10, 1920. The glass at the outer end of the conduit 1 is acted upon by the impeller 4, which may be a primary impeller cooperating with another or secondary impeller, as shown in Figs. 1, 2 and 3; or it may, as shown in Figs. 4, 5 and 6, be the only impeller employed. The lower end of this impeller moves in the path indicated by the dot-and-dash lines of Figs. 5 and 6 in successive cycles, propelling the glass forward and periodically raising its level in the container as shown in Fig. 6. The glass discharges through the outlet periodically in timed relation to the strokes of the impeller and forms below the outlet into successive gathers from which mold charges are severed by the shear blades 36 reciprocating below the outlet. The glass discharging from the outlet may be acted upon by the secondary impeller 5, or this secondary impeller may be omitted so that the discharge of the glass is controlled only by the periodically varying depth of the glass in the container, as shown in Figs. 4 to 6. The separated mold charges fall upon a moistened chute 208 and slide upon it to the molds mounted on the table of the associated glass-ware shaping machine.

The frame of the machine comprises columns 32 which surround the channel and the container. The columns 32 have suitable brackets at their upper ends to carry the drive shaft 33 and various pivot shafts. The drive shaft may be driven by a pulley 34, as shown. The shaft 33 carries cams 35 for driving the shears and serves as a bearing for other cams which drive the impellers.

The shear blades 36 are carried on the inner ends of carriers 53 guided between grooved guide rollers 54 pivoted on the columns 32. The carriers 53 are moved toward and away from each other by means of levers 56 suitably connected with the carriers 53 at their lower ends. The shear levers 56 are pivotally mounted on studs 60 and 61 carried on the columns 32. The upper ends of the shear levers are provided with cam rollers 62 which are held by suitable springs 63 against the shear cams 35 which are fixed on the main shaft 33, the cams being shaped to move the shear blades to and from each other to cut off the successive mold charges when formed.

The shear blades 36 are cooled between their successive severing operations by means of water sprays 86 (Figs. 1 and 2) supplied by pipes 87 and regulated by valves 88. The water from the spray strikes the blades in

their retracted positions and is finally caught by the drain pans 14 from which the water is drained away.

The impeller 4 is constructed of refractory material carrying a stiffening metal core 90 which may be suitably cooled. The impeller is fastened by the upper end of its core in a holder 92. The holder is carried at the end of a swinging arm 95 which is pivoted at its upper end on a pivot 96 about which the impeller is capable of horizontal swinging movement. To allow the raising and lowering of the impeller during its horizontal swinging movement the pivot 96 is carried by a vertically swinging guide arm 97 pivoted on a shaft 98. This guide arm 97 carries a lever 100, Figs. 8 and 9, pivoted on the pivot 96, and carrying a cam roll 101. The outer ends of the guide arm 97 and the lever 100 carry swivel blocks 102 and 103 which are connected by a screw 104 carrying a hand wheel 105. This screw is threaded into the upper swivel block 102 and revolves freely with a shouldered bearing against the lower swivel block 103. Thus by turning the hand wheel 105 the relative angular position of the guide arm 97 and lever 100 may be changed, changing the position of the cam roll relative to the guide arm. The effect of this is to change the vertical position of the impeller. The cam roll 101 bears against the cam 108 which is so shaped as to raise and lower the impeller as desired.

To impart horizontal swinging movements to the impeller, the swinging arm 95 is connected with an adjustable system of levers by the connecting rod 110, Fig. 9, and cams 111 and 112 are provided to oscillate the levers. On the shaft 113 is pivoted a lever 114 having an upwardly projecting arm 115 carrying a cam roll 116 and a downwardly projecting arm 117 carrying another cam roll 118. The upper cam roll 116 bears against the left hand cam 111 which serves to move the impeller from front to rear. The lower cam roll 118 bears against the right hand cam 112 which serves to move the impeller forwardly or toward the outlet. The two cams are shaped so as to impart the desired horizontal swinging movements to the impeller. The lower arm 117 of the lever 114 carries a pivot 120 on which an adjusting lever 121 is pivoted. The outer end of this adjusting lever 121 carries a pivot 122 on which a screw 123 is swivelled. The lever 114 also carries a pivot 124 on which a threaded socket 125 is swivelled. A sleeve 126 provided with a hand wheel 127 is threaded inside and outside and serves to connect the screw 123 with the socket 125. The threads on the screws and socket are respectively left handed and right handed, so that turning the hand wheel 127 will increase or decrease

the distance between the pivots 122 and 124, thus swinging the adjusting lever 121 about its pivot in relation to the lever 114. In this way, by turning the hand wheel 127 and changing the setting of the adjusting lever 121, the pair of pivots 132 to which the connecting rod 110 is pivoted may be raised or lowered, thus shortening or lengthening the effective driving radius of the system to decrease or increase the stroke of the impeller 4.

The connecting rod 110 is made in sections connected by springs so as to form a driving connection for the impeller yielding in both directions. This prevents damage which might be caused by the impeller striking obstructions or by working in glass which has become chilled. A pair of pivots 135 on the swinging arm 95 carry a yoke 136 (Figs. 7 and 9) through which the rod 110 is free to move. The pair of pivots 132 on the lever 121 carry a yoke 137 in which the rod 110 is threaded. This rod carries springs 138 and 140 which hold the loose collars 141 against the yoke 136 and which may be adjusted to yield at the desired pressure by turning nuts 142 and 143 which are threaded on the rod 110. This rod is enlarged where it passes through the yoke 136 to form shoulders against which the loose collars 141 bear, thus locating the yoke 136 in a definite position on the rod while allowing the yielding of the connection when necessary. At the end of the rod 110 is fixed a hand wheel 144 by means of which the rod may be revolved so as to screw it in and out of the yoke 137 to alter the effective length of the connection between the lever 114 and the swinging arm 95, thus allowing the working position of the impeller 4 to be shifted horizontally without altering the shape of the path through which it makes its periodic movements.

To further control the movements of the impeller 4, the impeller cams 108, 111 and 112 are so driven that the timed relation between the impeller and the shears may be altered while the machine is operating. The impeller cams are loose on the shaft 33. To this shaft is keyed a bevel gear 147, Fig. 8, which drives a bevel idler pinion 150 which in turn engages the bevel gear 151 formed at the right of the cam 112. The impeller cams are thus driven in a direction opposite to that of the shaft 33. The idler pinion 150 rotates on a stud 152 carried by a piece 153 which is loosely mounted on the shaft 33 and on which a worm wheel sector 154 is formed. At the upper end of the right hand column 32 is a bracket 155 which serves as a bearing for a shaft 156 carrying a hand wheel 157 and worm 158. This worm engages the teeth of the worm wheel sector 154, so that

by turning the hand wheel 157 the piece 153 may thus be rotated about the shaft 33, and the bevel pinion 150 may be advanced or retarded relatively to the shaft and the 5 drive gear 147. This has the effect of advancing or retarding the impeller drive cams 108, 111 and 112 relatively to the rest of the machine, thus advancing or retarding the operation of the impeller relatively to 10 the operations of the rest of the machine.

The raising and lowering cam 108, which governs the rise and fall of the impeller 4, and the swinging cams 111 and 112, which impart the horizontal swinging movements 15 to the impeller 4, are formed so that the end of the impeller moves in the closed path indicated by dot and dash lines in Figs. 5 and 6 in the direction shown by the arrows.

The effect of this motion is also illustrated in Figs. 5 and 6. In making its forward stroke, the impeller 4 pushes some of the glass before it, raising the level in the container 2 as shown in Fig. 6. This accelerates the discharge of glass through the 25 outlet 3 on account of the increasing pressure due to the increased gravity head. As the impeller moves backwardly, it carries some of the glass back with it and lowers the level of the glass in the container as 30 shown in Fig. 5. This has the effect of decreasing the gravity head of glass over the outlet and decreasing or retarding the discharge through the outlet. In this manner, the discharge of glass through the outlet is 35 periodically accelerated and retarded, thus giving a control of the discharging action.

The discharging glass accumulates below the outlet in successive suspended masses or gathers, from each of which a mold charge 40 is severed by the shears 36 which operate in timed relation to the strokes of the impeller. The time of accumulation and formation gathers is thus controlled by the strokes of the impeller, so that a suspended 45 gather is always present for the shears to sever a mold charge at each one of their strokes.

The size and general shape of the successive gathers, and of their resulting mold 50 charges, may be varied and controlled, while the machine is operating, by varying and controlling the extent, character and time of occurrence of the periodic rise and fall of the glass level in the container 2. 55 This may be done by the various adjustments provided in the parts driving and positioning the impeller 4. For the purpose of making these adjustments, the separate hand wheels above described have 60 been provided.

By turning the hand wheel 157 and altering the time of operation of the impeller 4 relatively to the other operations of the machine, the periodic glass depth variation 65 in the container is made to occur in

varying time relationship to the severing operation of the shears. The gather of glass accumulated below the outlet may thus be made to form sooner or later relative to the time at which it is severed, thus allowing more or less time for it to stretch or elongate before it is severed. Thus by turning the hand wheel 157 to advance the operation of the impeller 4, a longer and more attenuated mold charge may be delivered, while by retarding the operation of that impeller, a shorter and more compact mold charge will be delivered. By properly choosing the size of the outlet ring 70 75 24, the gathers suspended below the outlet 80 will have the desired diameter. The ratio of their length to their diameter and their general shape may then be controlled by the adjustments which have been described.

The impeller 4 just described may be used 85 as a primary impeller in conjunction with a secondary impeller 5 for the purpose of further controlling the extrusion and formation of the gathers below the outlet. This secondary impeller 5 is made of 90 refractory clay and is guided for vertical movement into or through the outlet ring 24, and concentrically therewith, by guide shafts 160 and 161, sliding in bearings 162 and 163 respectively, which are formed on 95 the container case 10, (Figs. 1, 2 and 3). The guide shaft 160 carries an arm 164 to which a split holder 165 carrying the secondary impeller 5 is detachably secured by 100 clamp screws 166.

The secondary impeller and its carrier are suspended by the connecting rod 173 and its pivots 174 and 175 from a horizontal lever 176 pivoted by its hub 177 on the hub of a vertical lever 178 which is pivoted 105 on the shaft 180. The two levers 176 and 178 are thus pivoted one on the other and on the shaft 180 as a common pivot. The vertical lever 178 has at its upper end a stud 181 carrying a cam roll 182 which bears 110 against the secondary impeller cam 183 (Fig. 3).

The secondary impeller cam 183 is composed of several parts as shown in Figs. 10 and 11 in left side elevation and in Fig. 8 115 in section. The greater portion of the working surface of the cam is formed in one piece with the hub 189 which is mounted loosely on the main shaft 33. The remainder of the cam surface is formed by two 120 removable lobes 190 and 191 which are attached to the main part of the cam by screws 192. The lobe 190 raises the impeller and is bolted in a fixed position on the main part of the cam by its screws. The lobe 191 which governs the fall of the impeller is slotted at 193 so that it may be 125 adjusted to various angular positions relative to the remainder of the cam as indicated by the graduations shown in Fig. 11. 130

In this way the lobe 191 may be set so as to increase or decrease the extent of the exposed circular portion 200 of the cam surface, which portion governs the dwell of the secondary impeller at its lowest position. In Fig. 10 the lobe 191 is shown set at a very short distance from the lobe 190 so as to give only a short dwell of the secondary impeller in its low position, 10 while in Fig. 11 the lobe 191 is shown set so as to give a dwell of the secondary impeller in its low position five times as long as that shown in Fig. 10. The cam lobes may be removed and exchanged for others giving 15 the secondary impeller a rise or fall of any desired character.

These cams for the secondary impeller are driven as follows: The main drive shaft 33, which revolves in the direction shown 20 by the arrow in Fig. 8, carries a bevel gear 196 (Figs. 7 and 8) which is keyed to it. This bevel gear drives an idler pinion 197 which in turn meshes with teeth cut in the right hand face of the secondary impeller 25 cam 183 which is thus rotated in the direction indicated by the arrow. The idler pinion 197 is carried by a stud 198 fixed in the lever 201 revoluble about the shaft 33 by means of a screw adjustment including 30 an adjusting screw 202 carrying a hand wheel 203 (Figs. 2 and 3) and fixed collars 204. The screw 202 is guided by a bearing in the bracket 205 and its longitudinal position is fixed by the collars 204. The screw 35 202 is threaded into a socket 206 pivoted to the lever 201 by the pivot 207. Turning the hand wheel 203 rocks the lever 201 about the shaft 33, moving the pinion 197 and advancing or retarding the secondary impeller 40 cam 183 relative to the drive bevel gear 196. Thus, and by similar mechanism, the times of operation of the primary and secondary impellers may be independently advanced or retarded in their timed relation to each 45 other and to the rest of the machine, and specifically in relation to the severing operation. These adjustments may be made while the machine is in operation, thus allowing the maintenance of the flow of glass 50 and the uniform heat conditions which are so essential in proper operation of glass feeding apparatus. Stopping of the machine to make adjustments would stop the delivery of glass and would have the effect 55 of allowing the glass to chill near the outlet and of changing the heat conditions. As a result, the operating conditions would be changed so that the immediate effect of the 60 adjustments could not be observed and employed as a guide in making these adjustments. In the present invention, on the other hand, these adjustments may be made while the apparatus is operating, so that the progressive effect of these adjustments 65 may be observed while they are being made,

thus giving immediate and better control of the operation.

One effect of advancing or retarding the secondary impeller cam is to make the rise of the impeller 5 earlier or later relative to the severing operation. The rapidity of the rising movement of the secondary impeller during the severing operation may thus be varied by taking advantage of the contour of the cam lobe 190 above described, 75 which is preferably shaped to give a gradually increasing speed to the impeller during the first part of its rise. By advancing the secondary impeller cam relative to the shear cams, the secondary impeller 80 may be made to rise more rapidly during severing, and by retarding the cam the secondary impeller may be made to rise more slowly during severing. The cam may also be set so that the secondary impeller begins to rise after the severing is partially 85 done.

In operating with both impellers, the primary impeller periodically raises and lowers the depth of the glass in the temporary 90 container 2 as shown in Figs. 5 and 6, and the discharge of glass due to this depth is modified by the action of the secondary impeller which reciprocates toward and from the outlet in timed relation to the 95 primary impeller. The molten glass issues from the outlet at a periodically varying rate under the combined influence of the gravity head created by the primary impeller 4 and of the accelerating and retarding 100 action of the secondary impeller 5, accumulating in gathers which are successively suspended from the outlet ring and from the end of the secondary impeller. For each complete stroke of the primary impeller 105 there is a vertical reciprocation of the secondary impeller and a reciprocation of the shears which sever a mold charge from each suspended gather. After each severing operation the freshly cut end or stub 110 remaining below the outlet and forming the lower end of the succeeding gather is moved upwardly, or its downward movement is retarded, by the action of the secondary 115 impeller.

In Figures 12 to 19, as to which this case is a division of my application Serial No. 294,792, also filed May 5, 1919, I have shown a form of my invention somewhat similar to that shown in the preceding figures, but omitting what was designated in connection therewith as the primary impeller. In these figures the forehearth 2^a has at its outer end a submerged outlet 3^a located in the outlet spout 212, the interior of which is shaped so as to coat with an impeller 213 mounted for vertical movement and provided with desired adjustment. As the glass issues periodically in regular cycles from the outlet it forms successive gathers from which 120 125 130

mold charges are severed by shear blades 4* reciprocating below the outlet. The separated mold charges fall upon a moistened chute 5* by which they are delivered to the mold. A gate 241 is provided for regulating the glass flow from the furnace to the forehearth. The position of this gate may be adjusted as desired and the glass in the furnace is preferably maintained at a higher level than that desired in the spout 212, so that the level or head desired in the spout may be maintained by adjustment of the gate.

The shear blades 4* may be mounted and actuated by mechanism similar to that disclosed in connection with the form of my invention shown in Figures 1 to 11, including a cam 268 on a drive shaft 261 and springs 290, the cams and springs being similar to the cams 35 and springs 63 before described.

The impeller 213 is guided for vertical movement into or through the outlet ring in a line concentric with this ring by guide shafts similar to those heretofore described in connection with Figures 1 to 11. The guide shaft 317 has an arm 322 in which is mounted the upper end of the impeller 213. The impeller is suspended by a connecting rod 330 from a lever 333 of similar construction and mounting to that heretofore disclosed. The lever is rocked, and therefore the impeller raised and lowered, by means of the impeller cam shown in outline at 343 in Figure 14, the roller 342 carried by the stud 341 on the lever being held against the cam by the weight of the impeller and its carrier.

The impeller cam is composed of several parts as shown in Figs. 16 to 18 inclusive. The sleeves 350 and 351 are loose on the main drive shaft 261 and are provided with bevel gears 352 and 353, respectively, at their outer ends, and with flanges 354 and 355 at their inner ends. The flanges form part of the cam surfaces and also hold removable cam lobes 356 and 357 which serve respectively to govern the rise and fall of the impeller. The lobe 356, which raises the impeller is carried by the right hand flange 355 and is removably secured to it by clamp screws 358 which enter slots 360 therein and serve to locate the lobe. The left hand flange 354 carries a lobe 357 which governs the fall of the impeller. This lobe is also detachably secured to the flange 354 by means of clamp screws 361 which enter slots 362 therein and thus locate the lobe. By this arrangement the two cam lobes can be revolved about the shaft 261 independently of each other so that their angular position relative to each other and around shaft may be varied within certain limits. For instance Figs. 15 to 18 show the lobes set 17½ degrees apart. A pin 359 is provided to

prevent separating them beyond the allowable limits.

The main drive shaft 261 revolves in the direction of the arrow shown on the drive pulley 262 (Fig. 12*) and drives the bevel gears 363 and 364 which are fastened to it. These bevel gears drive the pinions 365 and 366 which in turn drive the bevel gears 352 and 353 thus rotating the sleeves 350 and 351 with their cam parts, respectively. The pinions are mounted for rotation on holders 367 (Fig. 19), which are revolubly mounted on the main shaft 261 and provided with worm wheel sectors 370. These sectors are engaged by worms 371 (Fig. 19) carried on shafts 372 which are provided with hand wheels 373 and 374 respectively. By revolving the hand wheels the pinion holders 367 are rotated about the shaft 261, thus moving the sleeves 350 and 351 relative to the driving gears 363 and 364, respectively. This has the effect of angularly advancing or retarding the sleeves 350 and 351 bearing the cam lobes 356 and 357. In this manner the lobes may be set to act at any desired time relative to the shears and to each other. By turning the right-hand hand wheel 374, the right-hand sleeve 351 is advanced or retarded, thus advancing or retarding the cam lobe 356 by which the impeller is raised. By turning the left-hand hand wheel 373 the cam lobe 357, which governs the fall of the impeller, is advanced or retarded. By properly turning both hand wheels the same amount, both lobes as a whole may be advanced or retarded, correspondingly changing the time of the impeller operations relative to the time of the shear operations. In this manner the various characteristics of the impeller action may be varied, and its operating period may be advanced or retarded relative to the severing operation. For visibly indicating these adjustments of the impeller cams, the shafts 372 are provided with gear teeth meshing with teeth on indicator dials 375 which register with pointers 380.

One effect of advancing or retarding the cam lobe 356 by which the impeller is raised, is to make the up-stroke of the impeller earlier or later relative to the severing operation. These lobes are arranged so as to be readily changed by simply loosening the clamp screws which secure the lobes, and substituting other lobes.

In operation, the gate 241 is raised to the proper point to maintain the desired head of glass over the outlet and the machine is set in motion, reciprocating the impeller and the shears. The molten glass issues from the outlet under the combined influence of gravity and the action of the impeller, which times and controls its accumulation in gatherers which are successively suspended from the outlet ring and from the impeller end.

- For each complete reciprocation of the impeller there is a reciprocation of the shears which sever a mold charge from each suspended gather. After each severing operation, the freshly cut end or stub remaining below the outlet and forming the lower end of the succeeding gather, is moved upwardly, or its downward movement is retarded by the action of the impeller.
- 10 The impeller acts upon the glass partly by displacement and partly by adhesion of the glass to it. Consequently, as the impeller moves downward it gives a downward or extrusion impulse to the glass issuing 75 from the outlet. This extrusion impulse aids the gravity head at the outlet and increases the rate of discharge of the glass. As the impeller moves upward, it gives an upward or intrusion impulse to the glass within and below the outlet. This intrusion impulse opposes the gravity head at the outlet, tending to retard the discharge of glass from the outlet, and may be made to reverse 80 the motion of the glass within and below 25 the outlet, raising it up to an extent depending on the extent and strength of the impulse.
- Figures 20 to 28 illustrate a form of the invention herein claimed (this application 30 as to such figures being a continuation in part of my aforesaid application Serial No. 157,943) similar in many respects to the device shown in Figs. 1 to 11, and especially in Figures 4, 5 and 6. In it, as in such 35 figures, the molten glass flowing from the furnace along the spout or conduit 410 is swept in successive waves of suitable size for forming the desired gathers by means of the paddle or displacer 415, which is moved 40 forward and back in the glass of the conduit, thus propagating successive waves of glass which surge forward and are fed through 45 the outlet gap 416 in the end wall of the conduit in lieu of through the submerged 50 outlet of Figures 4, 5 and 6. A pocket 417 leading to the outlet gap 416 is preferably 55 formed by the converging walls 418 and 419 of the conduit. The paddle at the end of its forward movement enters the pocket 417 60 and more or less closely approaches the wall below the outlet. The paddle 415 is suspended for horizontal swinging movement 65 or an arm 420, the upper end of which is pivotally supported by a pivotal shaft 421. In order to enable the paddle to be raised and lowered during its horizontal swinging 70 movement the pivotal shaft 421 is supported in a vertical swinging arm 422, the forward end of which is pivotally mounted on the 75 shaft 423. As thus suspended, the paddle may be swung horizontally and raised and lowered, either independently or by a combination of these horizontal and vertical 80 movements. In the machine herein shown 85 such a movement is effected by means of a cam 425 controlling the horizontal swinging movements of the arm 420 on its pivot shaft 421 and a cam 426 which controls the vertical swinging movements of the arm 422 and its suspending arm 420 on the pivotal shaft 423. These cams and their operating connections with their respective arms are made adjustable by means which may be operated either independently, or in conjunction with each other, while the machine is in operation, so that the operator may, without stopping the machine and while watching the continued feeding of the glass, make the 90 adjustments, independently of each other, necessary to increase or diminish the size of the gathers, or to advance or retard the time of their formation and presentation to the shears.
- The advancing and retarding device is applied to the cams 425 and 426 as shown in section in Fig. 25. These cams are mounted side by side upon a sleeve 427, being secured thereto by means of a key 428. The sleeve turns loosely upon the main shaft 430 and is provided at one of its ends with a bevel gear 431, the teeth of which mesh with a bevel pinion 432 turning loosely on a stud 433, which is supported in radial relation to the main shaft 430 upon a sleeve 434 within which the main shaft 430 turns loosely. The bevel gear 435 is keyed to the main shaft 430, and meshes with the bevel pinion 432, which acts as an intermediate gear through 95 which the bevel gear 435 drives the sleeve gear 431 and the cams 425 and 426. Appurtenant to the sleeve 434 is a worm gear segment 437, the teeth of which mesh with a worm 436 journaled in a bracket 438, and having a hand wheel or knob 439 projecting from the front of the machine within convenient reach of the operator. With this device it will be obvious that the cams 425 and 426 will be rotated by the main shaft 430 through the bevel gears 435, 432 and 431 100 in a direction opposite to that of the shaft itself. By turning the sleeve 434 in the direction of rotation of the driving gear 435, the rotative position of the cams 425 and 426 will be moved back relative to the main shaft 430, and the other mechanisms of the machine, and the formation of the drops or gathers will be correspondingly retarded. If earlier formation of the drop or gather is desired, the sleeve 434 is turned, by means 105 of the handwheel 439 and worm 436, so as to carry the intermediate bevel gear 432 in a direction opposite that of its driving gear 435, which movement advances the rotary position of the cams 425 and 426 relative to the other mechanisms, thereby correspondingly advancing the period of formation of the gathers. With a right-hand worm 436 this advancing movement would be obtained 110 by turning the worm in the direction of the arrow shown upon the knob 439 in Fig. 20. 115
- 120
- 125
- 130

The horizontal swinging movements of the paddle are imparted by means of the cam 425 working against an anti-friction roller 447 appurtenant to the cam arm 448, mounted to turn freely upon the pivot shaft 449, which is supported in brackets 450 and 451. From the hub 453 of the cam arm depends a pair of quadrant arms 454 from which an adjustable connection is made with the paddle arm 420.

Spring 463 normally holds the cam roller against the cam 425.

As the succeeding waves of glass emerge from the outlet 416, they sag or settle down on the end of the trough or conduit, taking a more or less pear-shaped form and are severed at regular intervals by means of sheer mechanism operated in suitable time relation to the other mechanisms. The shear blades 500 are carried by shear slides 506 which are fitted for sliding movement in housings or casings 509, which substantially enclose the slides to protect them from dirt and pieces of glass. The casings 509 are mounted substantially opposite to each other on the columns 412 and 413, as shown in Fig. 20, and the shear slides are moved toward and away from each other by means of levers 511, which connect with the slides 506 by means of links 512. The shear levers 511 are pivotally mounted on studs 513 fixed in the columns 412 and 413. The upper ends of the shear levers are provided with studs 510 having friction rolls 514 which are held by suitable springs against the shear cams 515 and 516 fixed upon the main shaft 430, the cams being shaped and timed to bring the shear blades 500 together and cut off the successive drops or gathers at the proper times relative to the other mechanisms.

The effect of changing the period of the paddle movement, by advancing and retarding the time of that movement, is illustrated in Figs. 27 and 28, which show two different gathers, both of the same size, i. e. having the same volume of glass below the plane of severance indicated by the line α , at the time of severing. The shorter, more compact form of gather shown in Fig. 27 is obtained by retarding the period of the paddle movement, relative to the time of the severing operation, so that the fed mass of glass is pushed through the outlet only a sufficient length of time before the cutting operation to enable the gather to settle down a relatively short distance below the plane of severance before being severed. On the other hand, the longer gather of Fig. 28, having the same amount of glass as the gather of Fig. 27, results from advancing the period of paddle movement, so that the glass is pushed over the dam earlier, relative to the cutting action, and therefore has more time to elongate below the plane of severance before being severed. This varia-

tion is very desirable, in order to produce a gather approximating in form, and especially in dimensions, to the blank or parison to be made, which in turn approximates in form the article which is to be produced. Thus the gather of Fig. 27 is adapted for relatively short and wide forms of ware, while the gather of Fig. 28 is adapted for the making of bottles and other relatively long and narrow forms of ware. This practice closely approximates the well-known hand practice, in which the hand gatherer manipulates his gather, before placing it in the shaping mold, especially in blowing operations, so as to approximate the form of the mold cavity, which is, of course, the form of the ware made in that mold. As stated above, it is well understood that a skin or enamel is formed around the gather by its exposure to the air, and it is desirable, as in the hand practice, to make the gather approximate its succeeding or final form so as to avoid rupture or infolding of the skin by its shaping in the mold or in successive molds.

In all of the above described forms of this invention it will be seen that the issue of glass from a furnace may be variably timed in respect to the severing of the glass.

In the device shown in Figures 29 to 37 inclusive (as to which this case is a divisional continuation of my aforesaid prior application Ser. No. 713,143, filed August 3, 1912), the glass continually issues from the furnace and is intermittently in its motion past the severing plane by an implement interposed between the furnace and the said plane; which implement is also adapted to retract the stub left by each severing operation. The phase relation between the commencement of downward flow of the glass from the implement and the instant of severing, may in this structure be varied independently of the time relation between the commencement of retraction and the instant of severing. The device shown in these figures comprises a melting tank or furnace 601 containing the supply of molten glass 602 and provided with an outlet spout 603 along which a stream 604 of molten glass flows. A gate 605 made of refractory material is provided for regulating the size of the stream and for stopping it altogether when necessary. The spout 603 is preferably enclosed by a hood 609, for confining the heat to the flowing glass and maintaining it in suitable condition, which may be aided by gas jets 610.

The walls of the hood 609 extend down far enough to form a hot chamber enclosing the space wherein are formed the accumulating drops or gathers of glass, the chamber being large enough to allow the drops or gathers to accumulate to the required size without touching the walls of the chamber.

The stream of molten glass 604 flows from

the end of the spout upon a rotary gathering or accumulating head or punt 614, which is herein shown projecting through an opening in the side of the hood 609, the parts exposed to the heat being made of suitable refractory material. The head 614 is carried by a suitable stem or shaft 615, or any other suitable frame, which may be appurtenant to or integral with the general structure of the furnace. The shaft 615 is provided with a friction roller 617, through which rotary motion is communicated to the head from a friction disk 618, which is mounted upon a shaft 619 journaled in a bracket 620 and is driven by means of a belt applied to a pulley 621 from any convenient source of power.

The rotative speed of the gathering head may be varied by changing the size of the pulley 621, or the relative size of the friction roller 617 and the disc 618, or in any other convenient way.

In order to produce the desired intermissions in the rotation of the gathering head, to allow the accumulated gathers of glass to become suspended and severed therefrom, the peripheral driving surface of the friction disc 618 is interrupted as shown at 622 in Fig. 30, the relative length of the driving surface and of its interruption being proportional to the respective periods required for gathering and discharging drops or gathers of the required size to form the desired mold charges. Obviously, this will depend upon the size of the stream of glass flowing to the head, and the frequency of the operations. The size of the head should be properly proportioned to these conditions.

For convenience in thus proportioning and altering the alternating periods of rotation and rest of the gathering head, the friction disk is preferably made in two adjustable parts, as shown in detail in Figs. 36 and 37, the one part 665 being fast on the shaft 619 and the other 664 being clamped to the part 665 by a bolt 666 passing through a slot 668 in the disk 664, which permits these disks to be adjusted circumferentially relative to each other, so as to vary the length 667 of the circumferential interruption and thereby correspondingly vary the periods of intermission during which the gathering head rests from its rotation.

To sever the glass in the severing plane, I have shown, in Figures 29, 30 and 31, severing means comprising a pair of shears, the blades 627 and 637 of which are pivotally mounted upon a common center. The lower blade 627 is fixed upon a collar 628, appurtenant to a sleeve 629, which extends downwardly through and has a bearing in a bracket 630, the lower end of the sleeve having upon it a bevel gear 631 meshing with a driving bevel gear 632 upon the shaft 633.

journaled in a bracket 634. The upper blade 637 is secured to a collar 638, fixed to a shaft 639, which extends through and is journaled in a sleeve 629 and has fastened upon its lower end the bevel gear 640. Oscillating movement is communicated to the shaft 633 and its driving gear 632 by means of an arm 642, to which is pivoted a connecting rod 643 having upon its upper end a cam roll or pin 644 running in a cam groove 645 in the face of the cam 646, which is secured to and turns with the shaft 619. As a means of guiding the upper end of the connecting rod, it is here shown to be provided with a slot 647 through which the shaft 619 passes, a collar 648 being employed upon the outer side of the rod to retain it in position against the cam.

The drop or gather of glass, after being severed from the head, may fall directly into the mold or other receptacle for which it is intended, in case the construction and arrangement of the associated machinery enables this to be done; or, as shown in Fig. 29, the severed drop may fall upon transporting means such as a chute 651. The delivery end of the chute may extend to and above a mold 654, or succession of such molds upon a mold supporting table 655, or to any other arrangement to which the glass is to be delivered.

The rotary gathering head is here shown to be in the general form of a spheroid, the axis of which is preferably inclined, as shown in the drawings, to overcome the tendency, which the glass would otherwise have, of flowing along the stem or shaft 615. The head is supported at one of its poles by its connection with its stem or shaft 615. Its opposite pole is preferably provided with a polar protuberance 656, especially when the gather is likely to be large, relative to the surface of the head. This protuberance insures a more uniform distribution of the accumulating glass over the surface of the head, and appears to hold back the glass from flowing across that polar portion of the head during its rotating and accumulating period.

In the operation of this feeder, the stream of molten glass flowing against or upon the revolving surface of the head, and flowing thence sidewise toward the polar portions of the head, is thus distributed over the surface and accumulates thereon, as indicated by comparison of Figs. 32 and 33. When a sufficient amount of molten glass has thus been accumulated by the head, its rotation is slackened or stopped, and the glass at once begins to sag downwardly thereon as shown in Fig. 34, the greater portion of the glass thereon forming a pear-shaped drop 660, as shown in Fig. 35. The main body of the drop is connected to the head by an attenuating cord or thread 661. Severing

means, such as the shears illustrated and described herein, sever the attenuated neck at regular intervals and thus separate the drops from the portions above them, the drops falling into or upon the chute, or being otherwise taken care of, as may be desired. This leaves the head with the glass remaining upon it, and whatever amount of glass has flowed upon it during the severing operation, in approximately the condition shown in Fig. 29. Practically coincident with the severing operation, the head resumes its former rate and direction of rotation, thus winding up and absorbing the severed end of the thread 361.

The size of the drops formed may be varied by varying the volume or the rapidity of flow of molten glass to the head, or by varying the length of the interval from one stopping and severing operation to the next. The size of the head, its rotative speed, the time of the pause, and the time of rotation, may each or all be varied to give the desired results. Instead of stopping the head altogether to allow the glass to sag down and form the drop, its rotative speed may be merely diminished so that the glass upon the head flows down faster than it is carried up again by the rotating movement. Or the direction of rotation of the head may be momentarily reversed to allow the drop to form and be severed.

From the above it will be seen that the broader aspects of my invention are capable of being embodied in numerous forms of apparatus. To illustrate—

In the device shown in Figs. 1 to 11, the cycle of the paddle, and also the cycle of the secondary impeller, are adjustable, as a whole, and by unitary means, in respect to the time of shearing, the time of the downward stroke of the secondary impeller being capable of adjustment, by shifting a cam lobe, independently of the time of the up-stroke. This latter adjustment permits the duration of the feed period, and thus of the weight of the issued charge, to be varied without varying the periodicity of the machine, or conversely, permits the first two factors, duration of feed and weight of charge, to be held constant on variation of periodicity.

In the device shown in Figs. 12 to 19, the commencement of down-stroke and the commencement of the up-stroke of the impeller, are independently adjustable in respect to the time of severing, whereby also the duration of the feed period and the weight of the charges are capable of control with different periodicities.

In the device shown in Figs. 20 to 28, inclusive, the cycle of the paddle is adjustable as a whole by unitary means, in respect to the time of shearing, it being in this respect similar to what has been stated as to the

primary impeller of Figs. 1 to 11. In it the weight of the charge is determined by the character of the paddle stroke.

In the device shown in Figs. 29 to 37, however, the weight of the several charges is determined by the rate of flow to the punty, and the duration of the feed period to the shears should be such as to deliver this amount as separate charges and to prevent too great an accumulation of glass on the punty.

The set of diagrammatic figures 38 to 42 illustrate the scope of the more generic claims here made in being independent of the specific means employed for causing the glass to issue from the receptacle which contains it, and for intermitting the flow to produce mold charges.

Since the structures of Figs. 38 to 42 have already been described, it is sufficient to state at this point that Fig. 38 shows the punty feeder of Figs. 29 to 37; that Fig. 39 shows the paddle feeder of Figs. 20 to 28; that Fig. 40 shows the paddle-bowl feeder of Figs. 4 to 6, which may be considered as consisting of the paddle feeder with the addition of the bowl having a submerged discharge outlet; that Fig. 41 shows the paddle-needle feeder of Figs. 1 to 11, which may be considered to be the bowl spout feeder with the addition of the secondary impeller or needle, and that Fig. 42 shows the plunger feeder or needle feeder of Figs. 12 to 19, which may be considered the paddle-needle feeder with the paddle and dam omitted.

Figs. 38 to 42, when taken in numerical sequence, also show in convenient form the chronological order of the several original applications upon which the present application is based.

While I have shown these different embodiments of my invention for the purpose of illustrating the generic character of certain claims made herein, I have selected the form of the invention shown in Figs. 1 to 19 as the form to which the most specific claims of this application are directed, claims reading on other forms shown herein, and not on the forms shown in Figs. 1 to 19, being reserved by me and being made in the several original applications of which this is a continuation and in which such forms are shown, or in divisions thereof.

I also reserve for such original applications, or other divisions thereof, all claims which are directed specifically to adjustment of the stoppage, retraction or retardation of the glass in respect to the time of shearing; making, in this present application, claims drawn broadly (as distinguished from the specific steps above named) to the adjustment of the feed cycle, or steps therein, in respect to the time of shearing.

All claims made herein include changing

the time, in respect to shearing, of the delivery of the glass, or steps in such delivery, as distinguished from retarding, stopping or reversing the movement of the glass, and 5 claims reading upon the disclosure of this application, but not including such delivery features, are reserved by me to be made in other applications. Claims on many features of construction which are shown and 10 described but not claimed herein, are claimed in the various original applications or in divisions thereof.

I claim as my invention:

1. The method of controlling the shape 15 of mold charges periodically severed from molten glass, which comprises producing a succession of downward feeds of the glass, allowing each feed of glass to assume a desired shape under elongation by gravity 20 while suspended from above, and severing a charge from each feed, the time relation between the production of each downward feed and the time of severing of a charge therefrom varying with the desired shape. 25

2. The method of controlling the shape of mold charges periodically severed from molten glass, which comprises producing a succession of downward feeds of glass, allowing each feed of glass to assume a shape 30 under elongation by gravity while suspended from above, and progressively varying, during the feeding of the charges, the time relation between the production of each downward feed and the time of severing of a charge therefrom to produce a desired 35 change in the mold charges.

3. The method of controlling the shape 40 of mold charges periodically severed, while in suspension, from glass intermittently fed downwardly past a severing plane in a series of similar cycles by periodically acting severing mechanism, which comprises altering the time relation between the cycle of the feed of glass and of the severing mechanism. 45

4. The method of controlling the shape of mold charges of molten glass severed from gathers of the glass periodically discharged from an outlet, which comprises varying the 50 time of occurrence of discharge relative to the time of severing.

5. The method of varying the shape of 55 charges of molten glass suspended at the outlet of a container, which comprises successively impelling portions of glass from the container, severing gathers from the issued glass and advancing or retarding the impelling operation relatively to the severing operation.

6. The method of controlling the shape 60 of mold charges periodically severed from molten glass, which comprises periodically issuing the glass through a submerged outlet, allowing the issued glass to assume a desired shape under elongation by gravity 65

while suspended from above and severing a charge from the issued glass, the time relation between the issue of glass and the severing of a charge therefrom varying with the desired shape. 70

7. The method of regulating the shape of 75 mold charges of molten glass which comprises discharging the glass periodically through a submerged outlet, allowing the discharged glass to assume a desired form by elongation due to gravity, and severing mold charges therefrom in timed relation to the discharge, the interval between discharge and severing being selected in accordance with the shape desired. 80

8. The method of decreasing the diameter 85 of successive mold charges of equal weight periodically severed from molten glass periodically discharged in timed relation to the severing operation from an outlet below the surface of the glass in a container, which comprises altering this timed relation by advancing the time of occurrence of the discharge operation relative to the severing operation. 90

9. The method of increasing the diameter 95 of successive mold charges of equal weight, periodically severed from molten glass periodically discharged from an outlet below the surface of the glass in a container in timed relation to the severing operation, which comprises altering this timed relation by retarding the time of occurrence of the discharge operation relative to the severing operation. 100

10. The method of feeding molten glass in mold charges of controllable shape, which comprises discharging the glass through an outlet, periodically accelerating and retarding the discharge of glass through the outlet by downward and upward movements respectively of an implement in adhesive contact with the glass to form successive gathers of the glass suspended beneath the outlet, severing a mold charge from each suspended gather in timed relation to the motions of the implement, and varying the diameter of desired portions of the gathers by varying said timed relation. 110

11. The method of varying the shape of 115 successive charges of molten glass suspended at the outlet of a container, which comprises successively raising the head of the glass adjacent to the outlet, discharging glass from the outlet and severing gathers from the discharged portion at varying times relative to the time of discharge. 120

12. The method of regulating the shape 125 of mold charges periodically severed from molten glass discharged from an outlet below the surface of the glass in a container, which comprises periodically varying the depth of glass over the outlet in the container in timed relation to the severing operation, and altering this timed relation 130

during the continuance of the periodic operations.

13. The method of increasing the length of successive mold charges of equal weight, periodically severed from molten glass discharged from an outlet below the surface of the glass in a container, which comprises periodically increasing the depth of glass within the container in timed relation to the severing operation, and altering this timed relation by advancing the time of occurrence of the depth increase relatively to the severing operation.

14. The method of decreasing the length of successive mold charges of equal weight, periodically severed from molten glass discharged from an outlet below the surface of the glass in a container, which comprises periodically increasing the depth of glass within the container in timed relation to the severing operation, and altering this timed relation by retarding the operation of increasing the depth relatively to the severing operation.

15. Apparatus for separating molten glass into mold charges, comprising a container for the glass having a discharge outlet, means for governing the periodic delivery of the glass in successive suspended masses to a position below a shearing plane, shears operating at the said plane in timed relation to said governing means to shear a mold charge from each suspended mass, a receiver for a mold charge when severed located at a distance below the severing plane greater than the length of the charge severed, and adjustable control mechanism for variably controlling the time of said delivery relative to the time of shearing while maintaining the period between shearing operations constant.

16. Apparatus for separating molten glass into mold charges, including a container for the glass having an outlet, severing means operating periodically beneath the outlet, means for timing the suspension of successive gathers of glass beneath the outlet in timed relation to the operation of the severing means, and means for varying the time of beginning of the suspension period relative to the time of severing.

17. Apparatus for separating molten glass into mold charges, including a container for the glass having an outlet, severing means operating periodically beneath the outlet, means for timing the suspension of successive gathers of glass beneath the outlet in timed relation to the operation of the severing means, and means, operable during the continued operation of the apparatus, for varying the time of beginning of the suspension period relative to the time of severing.

18. Apparatus for feeding molten glass, including a container for the glass having

a discharge outlet below the surface level of the glass, shears adapted periodically to sever the glass beneath the outlet, an impeller coating with the outlet and mounted for vertical reciprocation, means for reciprocating the impeller vertically in timed relation to the shears, and means, operable during the continued operation of the apparatus, for altering the said timed relation.

19. Apparatus for separating molten glass into mold charges, comprising a container for the glass having a discharge outlet, means for governing the periodic delivery of the glass in successive suspended masses of a regulated volume to a position below a shearing plane, shears operating at the said plane in timed relation to said governing means to shear a mold charge from each suspended mass, and adjustable control mechanism for variably controlling the volume of said masses and the starting of their said delivery relative to the time of shearing, whereby the volume of the suspended masses and their extension below the shearing plane may be varied without varying the periodicity of the shearing operations.

20. The combination with apparatus for separating molten glass into mold charges, including a container for the glass having a discharge outlet, of periodically operated means for timing the formation and suspension of successive gathers of glass beneath said outlet, severing means operating periodically in timed relation to said timing means to sever a mold charge from each suspended gather, and means for altering the said timed relation between the severing and timing means.

21. Apparatus for separating molten glass into mold charges, including a container for the glass having an outlet, severing means operating periodically beneath the outlet, means for timing the discharge and suspension of successive gathers of glass beneath the outlet in timed relation to the operation of the severing means, and means for varying the time of beginning the suspension period relative to the time of severing.

22. Apparatus for separating molten glass into a series of mold charges, including a container for the glass having an outlet, severing means periodically operating below the outlet, means for intermittently feeding glass past the severing means in a series of suspended charges and for periodically retracting the glass at the severing plane, and means for varying the commencement of the feed and the cessation of such feed in respect to the operation of the severing means.

23. Apparatus for separating molten glass into mold charges, including a container for the glass having a discharge outlet, severing

- means operating periodically beneath the outlet, and means for varying the volume of glass discharged and timing its suspension in successive gathers beneath the outlet
- 5 in timed relation to the operation of the severing means, including means for varying the time of beginning the suspension period relative to the time of severing, whereby the volume of the suspended masses and
- 10 their extension below the shearing plane may be controlled.
24. The combination, in apparatus for feeding molten glass periodically in successive compact suspended masses, of periodically acting shears successively severing mold charges from the suspended masses, and means for maintaining the same length of the feed period upon increase or decrease of the frequency of cutting operations.
- 20 25. The combination, in apparatus for feeding molten glass periodically in successive compact suspended masses, of periodically acting shears for successively severing a mold charge from each suspended mass, and means for varying the length of the feed period without varying the frequency of severing operations.
26. In a glass feeding mechanism, the combination with a glass container having an outlet, an implement, driving means for periodically reciprocating the implement to determine the issue of glass from the container, shears for severing the issued glass, driving means for periodically actuating the shears, and means for changing the phase relation between the cycle of reciprocating movements of the implement, as a whole, and the cycle of movements of the shears.
- 40 27. Apparatus for feeding molten glass, including a container for the glass having a discharge outlet below the surface level of the glass, shears adapted periodically to sever the glass beneath the outlet, an impeller coating with the outlet and mounted for vertical reciprocation, means for reciprocating the impeller vertically in timed relation to the shears, and means for altering the said timed relation.
- 50 28. In apparatus for separating molten glass into mold charges, the combination of a container for the glass having a submerged discharge outlet, a vertically movable implement projecting downwardly into the glass in working alignment with the outlet, shears adapted to close beneath the outlet to sever mold charges suspended there beneath, and means for closing the shears periodically and reciprocating the implement vertically in timed relation to the shear operation, said means being adapted to permit adjustment of said timed relation while maintaining uniform reciprocations of the implement.
29. In apparatus for separating molten glass into mold charges, the combination of a container for the glass having a discharge outlet, periodically operable means for timing the formation and suspension of successive gathers of glass beneath said outlet, severing means operating periodically, in timed relation to said timing means, to sever a mold charge from each suspended gather, and means, operable during the continued operation of the apparatus, for altering the said timed relation between the said severing and timing means.
30. Apparatus for separating molten glass into a series of mold charges, including a container for the glass having an outlet, severing means periodically operating below the outlet, means for intermittently feeding glass past the severing means in a series of suspended charges and for periodically retracting the glass at the severing plane and independent means for varying the beginning of the intermittent feed and the cessation of such feed in respect to the operation of the severing means.
31. Apparatus for separating molten glass in a series of mold charges, including a container for the glass having an outlet, severing means operating below the outlet, means for intermittently feeding glass past the severing means and interrupting such feed, a common drive for the severing means and for the feeding and interrupting means, and independent means for varying the time of commencement of feed and of interruption of feed in respect to the operation of the severing means.
32. In apparatus for separating molten glass into mold charges, the combination with a container for the glass having a submerged discharge outlet, of means for periodically varying the depth of glass over the outlet, severing means beneath the outlet, means adapted to actuate said severing means in timed relation to the depth varying means, and means for altering said timed relation.
33. Apparatus for separating molten glass into mold charges, including a container for the glass having an outlet below the surface of the glass, means for periodically accelerating the gravity discharge of the glass through the outlet, severing means operating below the outlet in timed relation to the accelerating means, and means for altering the timed relation between the severing means and the accelerating means.
34. Apparatus for separating molten glass into mold charges, including a container for the glass having an outlet below the surface of the glass, means for periodically accelerating and retarding the gravity discharge of molten glass through the outlet, severing means beneath the outlet operating

in timed relation to the accelerating and retarding means, and means for varying said timed relation.

35. The combination of apparatus for feeding molten glass, including an outlet for discharging the glass, shears adapted to sever the glass beneath the outlet and means for applying periodic impulses to the glass in the outlet in timed relation to the shears, 5 of a cam covering the periodic application of the impulses, and provided with a shiftable cam lobe comprising a portion of the cam surface, and means for shifting the lobe to alter the timed relation between the 10 impulses and the shears.

36. Apparatus for feeding molten glass in a regular succession of freely dropping charges appropriate to the molds to be fed, comprising an impulsion chamber in communication with the tank of a glass melting furnace and having an outlet orifice submerged under a head of the molten glass, a plunger working in the glass above the orifice and serving in conjunction with the 20 surrounding walls of the impulsion chamber to exert impulses tending alternately to expel the glass through the orifice and to retard 25

its outflow, shear blades movable toward and from each other and coacting below and in line with but independently of the outlet 30 orifice to sever the suspended end of the issuing column of glass in timed relation to the plunger movements, and means for adjustably varying the movements of the shears and plunger with respect to each other to regulate the freely dropping mold charges severed by the shears, and to keep them uniform after the desired regulation is obtained.

37. Apparatus for separating molten glass 40 into mold charges including a container for the glass having an outlet below the surface of the glass, means for periodically accelerating and retarding the gravity discharge of molten glass through the outlet, means for 45 regulating the accelerating and retarding forces, severing means beneath the outlet operating in timed relation with the accelerating and retarding means, and means for altering said timed relation.

Signed at Hartford, Conn., this 24th day of November, 1925.

KARL E. PEILER.

in timed relation to the accelerating and retarding means, and means for varying said timed relation.

35. The combination of apparatus for feeding molten glass, including an outlet for discharging the glass, shears adapted to sever the glass beneath the outlet and means for applying periodic impulses to the glass in the outlet in timed relation to the shears, 10 of a cam covering the periodic application of the impulses, and provided with a shiftable cam lobe comprising a portion of the cam surface, and means for shifting the lobe to alter the timed relation between the 15 impulses and the shears.

36. Apparatus for feeding molten glass in a regular succession of freely dropping charges appropriate to the molds to be fed, comprising an impulsion chamber in communication with the tank of a glass melting furnace and having an outlet orifice submerged under a head of the molten glass, a plunger working in the glass above the orifice and serving in conjunction with the 20 surrounding walls of the impulsion chamber to exert impulses tending alternately to expel the glass through the orifice and to retard 25

its outflow, shear blades movable toward and from each other and coacting below and in line with but independently of the outlet 30 orifice to sever the suspended end of the issuing column of glass in timed relation to the plunger movements, and means for adjustably varying the movements of the shears and plunger with respect to each other to regulate the freely dropping mold charges severed by the shears, and to keep them uniform after the desired regulation is obtained.

37. Apparatus for separating molten glass 40 into mold charges including a container for the glass having an outlet below the surface of the glass, means for periodically accelerating and retarding the gravity discharge of molten glass through the outlet, means for regulating the accelerating and retarding forces, severing means beneath the outlet operating in timed relation with the accelerating and retarding means, and means 45 for altering said timed relation.

Certificate of Correction.

It is hereby certified that Letters Patent No. 1,573,742, granted February 16, 1926, upon the application of Karl E. Peiler, of West Hartford, Connecticut, for an improvement in "Feeding Molten Glass," were erroneously issued to "Hartford-Fairmont Company, of Hartford, Connecticut, a corporation of New York," whereas said Letters Patent should have been issued to *Hartford-Empire Company, of Hartford, Connecticut, a corporation of Delaware*; said corporation being assignee by mesne assignments of the entire interest in said invention, as shown by the records of assignments in this office; page 1, line 41, for the word "allow" read *allowed*, and line 72, for the word "stud" read *stub*; page 2, line 31, for the word "performed" read *preformed*; page 3, line 130, for the word "spray" read *sprays*; and page 5, line 43, after the syllable "mation" insert the words *of the suspended*; and that the said Letters Patent should be read with these corrections therein that the same may conform to the record of the case in the Patent Office.

Signed and sealed this 30th day of March, A. D. 1926.

DISCLAIMER

1,573,742.—*Karl E. Peiler*, West Hartford, Conn. FEEDING MOLTEN GLASS. Patent dated February 16, 1926. Disclaimer filed December 2, 1932, by *Hartford-Empire Company*.

Hereby disclaims said claims 1, 3, 4, 6, 7, 10, 30, 34, and 37 for the purpose of complying with what is understood to be required by law and to safeguard said owner's rights under the claims of said patent not hereby disclaimed; all without in any way modifying the scope, or affecting the validity, of said remaining claims.
[*Official Gazette December 27, 1932.*]
